UNITED STATES PATENT OFFICE.

JOHN G. SPEAR, OF WINSTED, CONNECTICUT, ASSIGNOR OF ONE-HALF TO
JAMES HARTNESS, OF SPRINGFIELD, VERMONT.

DESIGN FOR A STUD-BOLT.

SPECIFICATION forming part of Design No. 31,685, dated October 17, 1899.

Application filed September 5, 1899. Serial No. 729,562. Term of patent 14 years.

To all whom it may concern:

Be it known that I, JOHN G. SPEAR, of Winsted, in the county of Litchfield and State of Connecticut, have invented and produced a certain new and original Design for a Stud-Bolt, of which the following is a specification, reference being had to the accompanying drawings, forming a part thereof.

Figure 1 is a side view of a stud-bolt, showing my new design. Fig. 2 is a section on line 2 2 of Fig. 1.

As shown in the drawings, the leading or material feature of my design consists of the two smooth-surfaced portions *a b* between the two threaded portions *c c'* of a stud-bolt. The

said portions *a b* are of different diameters, the diameter of the portion *a* being substantially equal to the outside diameter of the threaded portions *c c'*, while the portion *b* is of lesser diameter, said portion *b* forming a recess between the portions *a* and *c'*.

I claim—

The design for a stud-bolt substantially as herein shown and described.

In testimony whereof I have affixed my signature in presence of two witnesses.

JOHN G. SPEAR.

Witnesses:

HENRY W. ROBINSON,
GEORGE L. FAUCHER.
